Primary Examiner — Michael C Stout*Assistant Examiner* — Katelin G Kloberg(74) *Attorney, Agent, or Firm* — Eversheds Sutherland (US) LLP(57) **CLAIM**

The ornamental design for a bassinet, as shown and described.

DESCRIPTION

FIG. 1 is a front, top perspective view of a bassinet, showing our new design;

FIG. 2 is a front view of the bassinet of FIG. 1;

FIG. 3 is a rear view of the bassinet of FIG. 1;

FIG. 4 is a left side view of the bassinet of FIG. 1;

FIG. 5 is a right side view of the bassinet of FIG. 1;

FIG. 6 is a top view of the bassinet of FIG. 1;

FIG. 7 is a bottom view of the bassinet of FIG. 1;

FIG. 8 is a front, top perspective view of the bassinet of FIG. 1, shown within an environment of use; and,

FIG. 9 is a front view of the bassinet of FIG. 8.

The broken lines depict portions of the bassinet that form no part of the claimed design. The additional broken lines in FIGS. 8 and 9 depict environmental subject matter that forms no part of the claimed design.

1 Claim, 9 Drawing Sheets(56)
